UNITED STATES PATENT OFFICE.

CHARLES ALCOTT GODDARD, OF SEATTLE, WASHINGTON.

DRY-KILN TRUCK.

SPECIFICATION forming part of Letters Patent No. 746,816, dated December 15, 1903.

Application filed September 5, 1902. Serial No. 122,258. (No model.)

To all whom it may concern:

Be it known that I, CHARLES ALCOTT GODDARD, a citizen of the United States of America, and a resident of the city of Seattle, in the county of King and State of Washington, have invented certain new and useful Improvements in Dry-Kiln Trucks, of which the following is a specification.

My invention relates to improvements in lumber-trucks, and has special reference to a device of this kind especially useful in lumber dry-kilns.

Among numerous objects obtained by this invention and readily understood from the following specification and accompanying drawings, included as a part thereof, is the production of a simple and inexpensive lumber-truck especially adapted for use in dry-kilns and embodying essential features of durability, general efficiency, and adjustability, which prolongs its usefulness, renders the truck of light weight, easy to operate, and reduces to a minimum the liability of breakage.

The above-mentioned objects are attained by the construction, combination, and arrangement of parts as disclosed on the drawings set forth in the specification, and succinctly pointed out in the appended claims.

With reference to the drawings filed here-with and bearing like reference characters for corresponding parts throughout, Figure 1 is a vertical transverse section of the truck, taken on line 1 1 of Fig. 2 and viewed as the arrows indicate. Fig. 2 is a vertical longitudinal section of one of the chairs or separations, taken on line 2 2 of Fig. 1 viewed as the arrows fly and indicated with a portion of one member comprising the bolster in relative position. Fig. 3 is a perspective view, on reduced scale, of one of the chairs or separators removed. Fig. 4 is a view in side elevation of the entire truck on small scale, and Fig. 5 is a plan view of same on like scale.

This elevation includes a chair, as 10, a bearing-wheel 12 rotatably mounted thereon, and a bolster comprising oppositely-disposed beams 14, supported on a plurality of said chairs. This chair comprises an open rectangular frame of considerable depth and of suitable length and width to receive a respective wheel, as 12, and preferably composed of a single piece of metal brought to the re-

quired shape by casting or the like. Adjacent the lower side edges of the chair suitable laterally-projecting ribs 15 are arranged as brackets, which preferably extend the full length of the chair and serve as extended bearings for the beams 14, and substantially midway the length of these sides suitable transversely-disposed apertures 16 are formed adjacent the lower edge to receive the ends of the axle, as 17, of the bearing-wheel, and bolt-receiving grooves 9 are formed longitudinally to the end walls of the chair to effect a more rigid connection of the bolster. The apertures 16 are so disposed that the upper portions thereof occur above the top edge of ribs 15, so that when the beams 14 are in place the lower edges thereof serve to prevent longitudinal displacement of the axle, which is thereby conveniently held in place and the use of set-screws, keys, or like fastenings for the purpose avoided and the height of the truck reduced to a minimum without sacrificing clearance above the traction-surface. As now considered each bearing-wheel is mounted on suitable rollers, as 18, placed about the axle 17, and consisting of sections of round rods, which are preferably rendered of less length than the inside width of the chair, Fig. 1, so that they are permitted to move longitudinally on the axle to partially compensate for lateral irregularities in the track. Each bearing-wheel is formed with oppositely-disposed tread-embracing flanges on the periphery and preferably rendered with the bore of less depth than the length of rollers 18, so that the wheel will have sufficient lateral play thereon to avoid binding against the side of the chair in case of cramping on the track, and in the present embodiment an annular recess 20 is formed in the bore of the wall concentric therewith and comprehends a reservoir to retain a supply of lubricant, as graphite or the like. This recess is preferably rendered substantially T shape, as viewed in cross-section, Fig. 1, and so disposed that the stem portions extend to the bore and forms a restricted annular opening between the head of the recess and bore, which prevents the passage of an excess of lubricant to the bearings of the wheel, while allowing the reservoir proper to be rendered of larger capacity, and furthermore leaves the major portion of

the wall of the bore unbroken for a more perfect bearing. Leading to the recess 20 is a suitably-disposed aperture 21, through which the lubricant is conveniently introduced, and as now considered this aperture is formed in the web of the wheel closely adjacent the bore and is preferably arranged in a substantially horizontal position to better prevent escape of the lubricant.

10 In the present construction the beams 14 comprise channel-bars composed of steel and are equal in height to the width of the side of the chair measuring upwardly from the top of the brackets 15, so that the top surface of 15 the truck is left even throughout. These beams are placed on said ribs 15 with their smooth side surfaces against the sides of the chairs and suitable apertures arranged in the web of the beams concentric with the grooves 20 9, formed in the end walls of the chair, and serve to bind said beams and chair firmly together.

In the present instance the truck is arranged with a chair adjacent each end of the bolster; 25 but in extremely long trucks a centrally-disposed chair may be added if desired.

The device thus presented is simple of construction, has few parts likely to get out of order, and can be quickly assembled. It furthermore embodies maximum strength with minimum weight, as it is not necessary to cut away large portions of the channel to afford journals for the axles, which instead are journaled in the side walls of the chairs in seats 30 of comparatively extensive length, and these bars have substantially long surfaces bearing upon the chairs, and can consequently be rendered correspondingly lighter without sacrificing strength. By the particular arrangement 35 for lubrication disclosed the bearings of the rollers are kept perfectly lubricated and the necessity for using oil for the purpose and resultant dangers of fire in the kiln avoided. Furthermore, the space afforded for lateral 40 play of the bearing-wheels on the rollers, as indicated, compensates for crookedness in the track, and thereby avoids cramping.

It will be understood that the lubricant normally lies in the lower part of the recess or 45 reservoir, and as the wheel is operated portions thereof cling to the wall of the bore and pass above the rollers, and a part then falls thereupon through the restricted opening, while the balance strikes upon the opposite 50 wall of the head of the recess and returns to normal position. It will thus be seen that the head portion of the reservoir can be made of sufficient size to contain a comparatively 55 large supply of lubricant, while but a limited portion thereof will pass to the bearings, and consequently the replenishing of the lubricant occurs at less-frequent intervals and a saving of time is effected.

Having thus described my invention, what 60 I claim as new, and desire to secure by Letters Patent of the United States of America, is—

1. In a truck, a chair comprising an open

rectangular frame, and a bracket formed along the outer surface of each of the opposite sides of the frame, said chair having 70 transverse bolt-receiving grooves in the outer surface of its ends.

2. In a truck, a chair comprising an open rectangular frame having axle-apertures formed in its opposite sides, and bolster-supporting brackets along the outer surfaces of the sides adapted to support bolsters across a portion of each aperture. 75

3. In a truck of the nature indicated; the combination with a chair comprising an open 80 rectangular frame of considerable depth, and having a rib extending along the lower outer edge of each side and an axle-aperture in each side with a portion thereof above said rib; of a bolster comprising oppositely-disposed beams 85 seated on said ribs and means to secure the beams to the chair.

4. In a truck of the nature indicated, the combination with an axle seated in separated supports; of rollers of less length than the distance between said supports and a wheel mounted thereon having a hub of less depth 90 than the length of said rollers.

5. In a truck, the combination with a plurality of chairs each comprising an open 95 rectangular frame provided with a rib along the lower outer edge of each side and having axle-apertures in said sides, each end wall of said chair having a bolt-receiving groove, and an axle in said apertures, of a bolster comprising oppositely-disposed channel-bars seated on said ribs, and binding-bolts connecting 100 said bars and lying in said grooves.

6. In a truck of the nature indicated; the combination with a chair comprising an open 105 rectangular frame of considerable depth, and an axle seated in the sides of said frame; of rollers on said axle of less length than the separation of the sides of said frame, and a wheel mounted on said rollers and having the 110 hub of less depth than the length of the rollers.

7. In a truck, a plurality of chairs each comprising an open rectangular frame, ribs along the opposite sides of the chair, a bearing-wheel rotatably mounted in each chair, 115 bolsters comprising oppositely-disposed bars seated on the ribs, and means for securing the bars to the chairs.

8. In a truck, a plurality of chairs each comprising an open rectangular frame, a 120 bracket formed on each of the opposite sides of the chairs, said sides having axle-apertures, each aperture having a portion above the bracket, axles supported in said apertures, bearing-wheels mounted on said axles, 125 bolsters comprising oppositely-disposed bars seated on said brackets, and means for securing said bars to the chairs.

9. A truck of the nature indicated; comprising a plurality of chairs each comprising 130 an open rectangular frame of considerable depth and having a bracket extending along the lower outer edge of opposite sides and axle-apertures in said sides with a portion

above the brackets, axles seated in said aperture-rollers on said axles of less length than the inside width of said frame, bearing-wheels with the bores of less depth than the length of said rollers mounted thereon and each having an annular recess in the wall of said bore substantially T shape in cross-section, a bolster comprising oppositely-disposed channel-bars seated on said brackets and means to bind said beams to the chairs.

10. In a truck, the combination with a

chair supported by a bearing-wheel, of a pair of oppositely-disposed channel-bars supported on the chair, and means for binding the chair between the bars to prevent lateral displacement of the bearing-wheel.

Signed at Seattle, Washington, this 4th day of August, 1902.
